United States Patent Office.

ANTON ZWIEBEL, OF BURLINGTON, WISCONSIN.

Letters Patent No. 68,542, dated September 3, 1867.

IMPROVED UNIVERSAL JOINT.

The Schedule referred to in these Letters Patent and making part of the same.

TO ALL WHOM IT MAY CONCERN:

Be it known that I, ANTON ZWIEBEL, of Burlington, in the county of Racine, and State of Wisconsin, have invented a new and improved Universal Joint; and I do hereby declare that the following is a full, clear, and exact description thereof, which will enable others skilled in the art to make and use the same, reference being had to the accompanying drawings, forming part of this specification, in which—

Figure 1 represents a side view of my universal joint.

Figure 2 is a vertical cross-section of the same, the plane of section being indicated by the line xx , fig. 1.

Figure 3 is a longitudinal sectional view through one of the knuckles and shanks.

Figure 4 is a cross-section of the same.

Similar letters of reference indicate like parts.

The object of this invention is to construct a universal joint that is to be used especially on threshing machines, which is made without projecting bolts or pins, and which can be easily taken apart for renewing the knuckle-pins when the same are worn out.

The invention consists in arranging long shanks for the attachment of the axles to the knuckles. These knuckles are provided with wooden pins, which turn in proper bearings in the ring. Said knuckles are so arranged that they can be easily removed from the ring, so that the aforesaid wooden pins may be renewed when they are worn out.

The universal joints now used are very dangerous, by reason of bolts and joints projecting beyond the ring, and many accidents have already occurred on this account. My invention not only overcomes this difficulty and objection, but is furthermore so constructed that it will last for a very long time, as the wooden pins can be easily renewed when worn out.

A is the ring, which is made of cast iron or any other suitable material. Within the same are arranged four pairs of semicircular flanges, a and b , which form the bearings for the knuckles. Each pair, a and b , of these flanges is arranged so that the pin B of the knuckles can be inserted between them. Two pairs of these flanges are arranged on either end of the ring A in such a manner that the pins of the knuckles will be held therein at right angles from each other. The wooden knuckle-pin B is secured in the end of the shank C, which is provided with a ring, c , at its end, for the reception of the pin B. The shank C itself is provided with a square hole, (see figs. 3 and 4,) so that the shaft may be easily attached thereto. From each end of the ring C, through which the pin B passes, projects a lip, d , as shown in fig. 2. The knuckle can be secured or placed into the ring, by laying the shank upon the edge of the ring. The pin B will then pass into the space between the flanges a and b . But as soon as the shank is turned the lip d will also be brought between the flanges, and the knuckle is then firmly held in the ring, and can be removed only by turning it to one side as far as possible, so that the shank rests upon the edge of the ring.

Both knuckles are arranged alike, and operate both as described. When the wooden pin is used up it may be easily replaced; and the whole device is therefore simple, compact, and easily repaired, and its use is not connected with any danger to the attendants of the machine.

What I claim as new, and desire to secure by Letters Patent, is—

The combination of the ring A, having semicircular flanges a and b , wooden pin B, lips d on knuckles c , and shank C, all constructed as described for the purpose specified.

ANTON ZWIEBEL.
